UNITED STATES PATENT OFFICE

JOSEPH P. CROWLEY, OF TOLEDO, OHIO, ASSIGNOR TO LIBBEY-OWENS GLASS COMPANY,
OF TOLEDO, OHIO, A CORPORATION OF OHIO

SHEET-GLASS-SURFACING APPARATUS

Application filed January 7, 1926. Serial No. 79,705.

The present invention relates to sheet glass surfacing apparatus.

An object of the invention is to provide an apparatus, particularly well adapted for the surfacing of flat glass, and includes means whereby a plurality of surfacing members are moved upon the sheet to surface the same.

Another object of the invention is to provide an apparatus of this nature wherein each of the polishing blocks are reciprocated upon the sheet being surfaced, while at the same time each block is rotated upon its own axis.

Another very important object of the invention is to provide a sheet glass surfacing apparatus wherein the sheet is rotatably carried by a table, the machine including a plurality of surfacing members arranged in substantially circular formation, the center of the formation being offset from the center of the sheet, whereby each of the blocks is reciprocated upon the surface of the sheet, while at the same time each block is rotated upon its own axis, permitting the sheet to be surfaced in a minimum amount of time.

A further object of the invention is to provide surfacing apparatus adapted for the production of plate glass, wherein a sheet of glass may be freely supported upon a rotatable table, the surfacing means including a substantially circular frame carrying a plurality of rotatable surfacing members, the center of the frame being offset from the center of the sheet to produce the necessary relative movement between the sheet and the surfacing members to attain the desired surfacing.

A further object of the invention is to provide an apparatus of this nature wherein the surfacing unit comprises a substantially circular spider, carrying a plurality of rows of polishing blocks in a manner that each of the polishing blocks is rotated about the axis of the spider, while at the same time each block is rotatable about its own axis.

A still further object of the invention is to provide an apparatus adapted for the production of plate glass, and includes a positively driven table which supports the sheet and a surfacing unit arranged thereabove, the surfacing unit including a circular spider

carrying a plurality of rotatable polishing blocks, the center of the spider being offset from the center of the sheet, and each of the polishing blocks being rotated by reason of the frictional contact with the sheet being surfaced, the spider and blocks being movable to and from the said sheet.

Other objects and advantages of the invention will become apparent during the course of the following description.

In the drawings wherein like numerals are employed to designate like parts throughout the same,

Fig. 1 is a top plan view of the surfacing apparatus,

Fig. 2 is an elevation thereof, partially in section, for the purpose of illustration,

Fig. 3 is a sectional view of a portion of the apparatus,

Fig. 4 is a plan view of one form of abrasive distributing means which may be used, and

Figs. 5 to 9, inclusive, are diagrammatic views of the movement of one of the polishing units in one revolution of the apparatus.

In the production of plate glass, a flat blank is ground and polished on both sides to produce a sheet which is practically free from any surface irregularities, the two surfaces being parallel to each other. Ordinarily, both sides of the sheet are first ground and then polished. Although the forms of abrasives vary in different methods, quite frequently a form of sand is used in the grinding end, while rouge is used in the polishing. In the present application the word "abrasive" is used to mean both the sand and the rouge.

In the drawings the invention has been illustrated as used in connection with a machine wherein the sheet remains upon a single table during one portion of the surfacing operation, namely, the polishing of the sheet. In some processes the sheet to be surfaced is moved under a plurality of grinding and polishing units, this type of apparatus being known as the continuous process. It is to be understood that the present invention is not limited to any one type of process.

In the drawings, the numeral 10 designates

a table upon which the sheet 11 to be surfaced is supported. In the particular apparatus disclosed, the sheet is freely supported in a recess 12. This differs from the ordinary type of apparatus used in that the usual practice is to cement the sheet upon a table by means of plaster of Paris. The table 10 is positively driven by some suitable source of power.

Arranged above the table 10 and the sheet 11, in the recess 12, is a substantially circular spider 13, carried by a hollow rotatable shaft 14, rotatable in a sleeve bearing 15. A housing 16 is provided, and the construction as a whole is supported upon the frame work 17. The sleeve 15 is provided with a rack bar portion 18 which is adapted for engagement with a segmental gear 19 supported upon shaft 20 and operable by means of a pitman 21, driven through means of the gear arrangement 22, connected to the source of power 23. The pitman 21 is also provided with an arm 24 pivotally mounted on a stub shaft 25, and carrying a pulley 26 at the opposite end. A cable 27, having the end 28 secured to the frame 17, is trained about the pulley 29 and is connected to a guard 30 which surrounds the table 10. The guard 30, during the operation of the machine, is in a position similar to that illustrated in Fig. 2 to prevent the abrasive used from being thrown off onto the floor. When it is desired to examine the sheet or remove the same, the pitman is operated so that the spider 13 is raised and the guard 30 is lowered. By properly reversing the action, the spider 13 is lowered and the guard 30 is raised.

The spider 13 is adapted to rotatably support a plurality of surfacing members 31. As shown in the drawings, there are four rows of these surfacing members, the sizes of the said members varying. Of course the number of rows shown and the size of the blocks can be varied as desired without departing from the spirit of the invention. Each of the members 31, which are shown in the drawings as polishing blocks, is carried by a spindle 32, operable through a journal 33 in the spider 13. The end of the spindle 34 is of a nature to prevent accidental displacement of the block when the spider is moved vertically from the sheet. As can be seen upon rotation of the spider, each of the polishing blocks is rotated about the shaft or the center 14. The shaft 14, which is the center of the spider, is offset from the center of the table 10, and likewise the center of the sheet 11. Upon rotation of the table 10, and due to the frictional contact between the sheet and the blocks 31, the spider will be caused to rotate, and in rotating each block will be reciprocated upon the sheet, while at the same time it will rotate about its own axis, as well as the axis of the spider as an entirety. In Figs. 5 to 9, inclusive, is illustrated diagram-

matically the movement of one of the outer blocks in one revolution of the spider. Fig. 9 shows how much surface one block covers in one rotation, and considering the number of blocks carried by the spider it will be seen that the relative movement between the blocks and the sheet is so great that very little of the sheet remains exposed at any one time, and that the time required for surfacing the sheet will be very low.

In order to supply abrasive between the sheet and the blocks, a plug 35 is placed in the end of the hollow shaft 14. The plug is provided with a plurality of openings 36 to which are connected conduits 37. Fig. 4 clearly shows one arrangement of conduits which may be used. The conduits are arranged under the spider and are adapted to introduce a sufficient quantity of abrasive upon the sheet to permit proper surfacing thereof. The abrasive is initially drawn from a suitable source of supply and is permitted to discharge into a hopper or funnel 38, supported at the upper end of the hollow shaft 14.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

Claims:

1. A runner construction for use in machines for polishing flat glass, including a rotatable runner frame, an outer annular series of polishing blocks carried by said frame and being of a uniform size, a second annular series of polishing blocks carried by the frame inwardly of the first series and being of a plurality of sizes alternately arranged, a third annular series of polishing blocks carried by the frame inwardly of the second series and being also of different sizes alternately arranged, and a fourth annular series of polishing blocks carried by said frame inwardly of the third series and being of a uniform size.

2. A runner construction for use in machines for polishing flat glass, including a rotatable runner frame, an outer annular series of polishing blocks carried by said frame and being of a uniform size, a second annular series of polishing blocks carried by the frame inwardly of the first series and being of a plurality of sizes alternately arranged, a third annular series of polishing blocks carried by the frame inwardly of the second series and being also of different sizes alternately arranged, and a fourth annular series of polishing blocks carried by said frame inwardly of the third series and being of a uniform size, the larger and smaller polishing blocks of the second and third series being of substantially the same sizes respectively and all smaller

than the blocks of the first series and the blocks of the fourth series being of substantially the same size as the smallest blocks of the second and third series.

5 Signed at Toledo, in the county of Lucas and State of Ohio, this 5th day of January, 1926.

JOSEPH P. CROWLEY.
